[57] ABSTRACT

A multisection chain-flite conveyor for moving comminuted material such as cattle feed has an adjustable elbow between the juxtaposed ends of two conveyor sections to enable relative vertical pivotal adjusting

movement between the two sections. Each conveyor section comprises a supporting framework and a bed mounted thereon and sprockets are located at the remote ends of the multisection conveyor for supporting an endless chain arranged alongside the beds which has spaced apart flites attached thereto. The elbow comprises two pivotably interconnected elbow sections, each attached to the inner end of a conveyor section, and each elbow section comprises a pair of laterally spaced apart side plates joined together by a cross brace which also serves to support one end of its associated conveyor bed. The two elbow sections are relatively pivotable about a horizontal upper pivot shaft. A horizontal lower shaft is mounted between the side plates of one of the elbow sections below the upper shaft. Upper and lower chain guide rollers are rotatably mounted on the upper and lower shafts, respectively, and the upper and lower sides of the chain ride on the upper sides of the upper and lower rollers, respectively. A curved flite guide is mounted over the hub of the lower roller to prevent interference with the flites on the lower side of the chain. Overlapping tilt shields connected to the cross braces of the two elbow sections bridge the gap between the juxtaposed ends of the conveyor section beds. The upper roller rotates on the upper pivot shaft and thus prevents ear on the tilt shields.

FIG. 19

**MULTISECTION CONVEYOR HAVING
ADJUSTABLE ELBOW BETWEEN ADJACENT
CONVEYOR SECTIONS**

BACKGROUND OF THE INVENTION

1. Field of Use

This invention relates generally to chain-flite conveyors, such as are used in agriculture, to move comminuted material, such as feed or silage, from one location to another. In particular, it relates to multi-section chain-flite conveyors having adjustable elbow means for connecting the juxtaposed ends of adjacent sections to permit those sections to be positioned in a desired angular relationship with respect to each other.

2. Description of the Prior Art

It is common practice in agriculture to employ chain-flite conveyors to move feed or silage from one location to another, as from a silo to a cattle feeding bunk. Because physical conditions, building arrangements and special requirements on farms vary, some chain-flite conveyors are designed and manufactured so that basic and various optional components can be assembled in various combinations to provide a customized conveyor suitable for particular needs. Typically, the basic components of such a chain-flite conveyor comprise a supporting framework, a bed supported on the framework, a sprocket-supported chain-flite assembly for moving material along the conveyor bed, and drive means including an electric motor for driving the chain-flite assembly. Optional components may include mounts or hangers for the framework, a hopper for the fill-end of the conveyor, a spout for the discharge end of the conveyor, bed covers and so forth.

Furthermore, in some such conveyors the supporting framework and bed take the form of modular sections which can be rigidly secured together directly in end-to-end relationship to provide a conveyor of desired length. To further increase versatility, conveyor elbow assemblies of various angular size are provided for rigid interconnection between the ends of adjacent conveyor sections to enable them to be positioned in a desired angular relationship with respect to each other. For example, by means of an elbow of appropriate angular size one section could be disposed horizontally (or sloped upwardly) and another section could be sloped downwardly from either end thereof. Such elbows permit customized conveyor installations and are especially useful in conveyors which must extend over obstructions, such as walls, fences or the like. However, since each elbow has a specific angular configuration, extremely accurate layout of a proposed installation is required and, even then, a selection of differently sized elbows and trial and error fitting is sometimes necessary. Furthermore, once a particular elbow is selected, rearrangement or relocation of the conveyor is seldom possible unless one or more elbows of another size are available.

SUMMARY OF THE INVENTION

In accordance with the present invention there is provided a multi-section chain-flite conveyor having an adjustable elbow for connecting the juxtaposed ends of two adjacent conveyor sections to permit them to be adjustably positioned in a desired angular relationship with respect to each other about a horizontal axis within the design limits of the adjustable elbow. The in-

vention is advantageously employed in a conveyor wherein one upwardly sloped section supplies feed to the end of an adjacent section having a tapered bed and which is horizontally mounted above a cattle feeding bunk into which feed is evenly dispensed from the tapered bed.

Each conveyor section comprises a rigid supporting framework upon which the bed is mounted. The conveyor employs a chain-flite assembly comprising a single endless flexible chain which extends the entire length of the multi-section conveyor along one side of the beds and is reeved around sprockets rotatably mounted near the outer or remote ends of the conveyor. One of the sprockets is driven by an electric motor. Flites attached to the chain at spaced apart intervals there along and extending transversely of the conveyor bed pass above and below the bed as the chain moves. The flites passing along the upper surface of the bed move the material along the bed when the chain is in motion.

The adjustable elbow comprises two pivotally interconnected elbow sections, ends of which is rigidly connected to the inner end of one conveyor section. Each elbow section comprises a pair of laterally spaced apart side plates which are rigidly interconnected by a cross brace which also affords support for an end of the bed of the associated conveyor section. A horizontal upper shaft extends through holes in the side plates of the two

elbow sections and serves as a pivot shaft about which the two elbow sections (and attached U-shaped bed sections) are adjustably pivotable. A horizontal lower shaft is connected between the side plates of one elbow section below the upper shaft. Upper and lower chain

guide rollers are rotatably mounted on the upper and lower shafts, respectively, near one end thereof. The upper and lower sides of the chain ride on the upper side of the upper and lower chain guide rollers, respectively. A curved flite guide shield is located between

the side plates supporting the lower shaft and is disposed above the lower roller hub to prevent interference with the flites being moved by the chain. Overlapping tilt shields are connected to the cross braces on the two elbow sections to bridge the gap between the adjacent ends of the beds on the juxtaposed conveyor sections. The upper roller rotates on the upper pivot shaft and is extended above the shields to hold the chain above the shields and thus prevent wear on the tilt shields and of the chain.

The adjustable elbow enables two conveyor sections to be connected together in such a way that one conveyor section may be disposed in a horizontal plane, for example, and the other conveyor section may be placed in a sloped relationship with respect thereto. Thus, a conveyor having an elbow in accordance with the invention may be readily mounted over walls or other obstructions and can be easily adjusted, within design limits, to suit particular conditions. An elbow in accordance with the invention is especially well-suited for

use in chain-flite conveyors and the guide rollers facilitate chain-flite movement from one plane to another. The overlapping tilt shields prevent or limit feed from falling through the gap between the ends of the bottom beds, yet do not interfere with relative movement between the elbow sections. An adjustable elbow in accordance with the invention is relatively easy and economical to manufacture and install and is reliable in

operation. Other objects and advantages will hereinafter appear.

DESCRIPTION OF A PREFERRED EMBODIMENT

General Arrangement

Referring to FIG. 1, there is shown an elongated cattle feeding trough or feed bunk 10 which is supported above ground by a plurality of spaced apart frame members 11 each of which includes a cross bar 12. One section 14A of an elongated conveyor 14 in accordance with the invention is supported over bunk 10, being rigidly attached to the cross bars 12 of the frame members 11 by adjustable support brackets 15. Another section 14B of conveyor 14 is shown as sloping downwardly over a wall W and is located adjacent two silos S1 and S2. The section 14B of conveyor 14 comprises a pair of adjustable hopper and feed levelers (hereinafter referred to as hopper-levelers) 16, each

located beneath a chute on the silos S1 and S2 and cat-
5 tle feed in the form of grain or silage can be supplied to either or both hopper-levelers 16 as required. As hereinafter explained in detail, conveyor 14 operates in such a manner that feed supplied to section 14A thereof by section 14B is distributed evenly along the entire length of bunk 10. It may be assumed for purposes of illustration that bunk 10 and section 14A of conveyor 14 are co-extensive and that each is about 50 feet long, whereas section 14B of the conveyor is about 30 feet long.

Generally considered, with reference to FIGS. 1 through 8, section 14A of conveyor 14 comprises a rigid support framework 18 on which a tapered bed

15 20A, a chain-flite assembly 22, drive means 23 for driving the chain-flite assembly, and a cover 24 are mounted. Section 14B of conveyor 14 also comprises a rigid supporting framework 18 on which an unta-
20 ppered bed 20B, the chain-flite assembly 22, a cover 24, and the two hopper-levelers 16 are mounted. For convenience and versatility, the supporting framework 18 and cover 24 in each section may be constructed in short interconnectable lengths so as to enable fabrica-
25 tion of a conveyor 14 of any desired length. As FIGS. 5, 6, 7 and 8 show, the supporting framework 18 of each section 14A and 14B comprises a pair of spaced apart sides 30 and 31 which are rigidly joined together at intervals therealong cross braces 32. The tapered bed 20A of section 14A extends toward the remote end 30 of conveyor 14 from its opposite end whereat feed is deposited by section 14B. Chain-flite assembly 32 employs a single endless expandable link type chain 33 which extends substantially along the entire length of conveyor 14 and alongside the tapered edge of bed 35 20A of section 14A. Chain 33 is provided with flites 34 which are rigidly attached thereto at spaced apart intervals therealong and extend transversely of bed 20. Chain 33 is supported so that the flites 34 on the upper side of the chain slide along the upper surface of bed 40 20 and toward the remote end of conveyor 14 and the flites 34 on the lower side of the chain travel in the reverse direction beneath the bed as the chain is moved. Chain 33 is supported by sprocket assemblies 40 and 42 which are located at opposite ends of conveyor 14, i.e., at the outer ends of the sections 14B and 14A, res-
45 pectively. Sprocket assembly 40 comprises an idler sprocket 44 about which chain 33 is reeved. Sprocket assembly comprises a driven sprocket 46 about which chain 33 is reeved. Drive means 23, including an electric motor 45, are associated with sprocket assembly 42 and drive the driven sprocket 46 so as to move chain 33 and the flites 34 thereon in the abovementioned direction. A manually operable motor control in the form 50 of a push-button switch 48 is provided for motor 45 to enable the operator to start and stop the motor. As hereinafter described, each hopper-leveler 16 comprises means to deposit feed on bed 20B and also has feed leveler means on one end thereof to level the feed being moved toward section 14A by chain-flite assem-
55 bly 22.

In operation, feed is supplied to either or both hopper-levelers 16 from the silos S1 and S2. Feed is deposited from hopper-leveler 16 onto bed 20B of section 14B and then is moved therealong by the flites to bed 20A of the other section 14A. Feed is then distributed along the entire length of bunk 10 from tapered bed 60 20A.

In accordance with the present invention there is provided an adjustable elbow 200 for connecting the juxtaposed ends of the two adjacent conveyor sections 14A and 14B to permit those sections to be adjustably positioned in a desired angular relationship vertically with respect to each other and about a horizontal axis.

The adjustable elbow 200 comprises two pivotally interconnected elbow sections 201 and 202 each of which is rigidly connected to the inner end of one conveyor 14B and 14A, respectively. Elbow section 201 (connected to section 14B) comprises a pair of laterally spaced apart side plates 205 which are rigidly interconnected by a cross brace 206, which brace also affords support for an end of the bed of the associated conveyor section 14B. Elbow section 202 (connected to section 14A) comprises a pair of laterally spaced apart side plates 207 which are rigidly interconnected by a cross brace 208, which brace also affords support for an end of the bed of the associated conveyor section 14A. A horizontal upper shaft 211 extends through holes in the side plates of the two elbow sections 201 and 202 and serves as a pivot shaft about which the two elbow sections (and attached conveyor sections) are adjustably pivotable. A horizontal lower shaft 214 is connected between the side plates of elbow section 201 below the upper shaft 211. Upper and lower chain guide rollers 216 and 220, respectively, are rotatably mounted on the upper and lower shafts 211 and 214, respectively, near one end thereof. The upper and lower sides of the chain 33 ride on the upper sides of the upper and lower chain guide rollers 216 and 220, respectively. A curved flite guide shield 222 is located between the side plates 205 supporting the lower shaft 214 and is disposed above the latter shaft to prevent interference with the flites 34 being moved by the chain 33. Overlapping tilt shields 226 and 228 are connected to the cross braces 206 and 208, respectively, on the two elbow sections to bridge the gap between the ends of the beds on the juxtaposed conveyor sections.

The Supporting Framework

The supporting framework 18 serves as the basic support for all stationary and movable components forming conveyor 14 and also serves as the means by which section 14A is supported or suspended over bunk 10. As hereinbefore mentioned the supporting framework 18 of each section 14A and 14B is constructed of modular, interconnectable components, sections or units such as 14C in FIG. 1. In the embodiment shown, several such units 14C are employed in section 14A and five in section 14B. The supporting framework 18 in each section 14A and 14B comprises a pair of spaced apart sides 30 and 31 which are rigidly joined together at intervals therealong by cross braces 32 and 32a. Each side 30 and 31 comprises a side member 50 in the form of a channel shaped length of sheet metal which has a stiffening or strengthening member 51 in the form of a length of angle iron welded along the lower edge thereof. Vertically disposed coupling members 52 are welded to the outside of channel member 50 near the ends thereof to enable two adjacent sections such as 14A to be secured directly together in end-to-end relationship as by bolts 55 or to the elbow 200. Side 30 of supporting framework 18 is provided with a chain support member 56 which takes the form of a length of angle iron which is welded to the inside surface of side member 50. As FIG. 4 shows, bracket members 57 are

rigidly secured where necessary along the sides of 30, 31 (or at the ends of a section) and are part of or connected to the brackets 15 which support section 14A. The cross braces 32 take the form of tubular members which are rigidly secured as by welding to support brackets 58 which themselves are secured to the interior sides of the side members 50 by bolts 59. The cross braces 32a are welded directly to the side members 50. Covers 24 for each section 14A or 14b take the form of one or more lengths of curved or upwardly bowed sheet metal which are secured to the upper flanges of the side members 50 by bolts 60.

The Conveyor Beds

Section 14B of conveyor 14 comprises a rectangular bed 20B and section 14A comprises a tapered bed 20A. The tapered bed 20A extends toward the remote end of conveyor 14 from the opposite end wherat feed is supplied by section 14B. The beds 20A and 20B may be made of sheet plywood or other materials cut to appropriate size and bed 20A is cut at a suitable angle. The beds 20A and 20B rest on the cross braces 32 and 32a of supporting framework 18 and are rigidly secured to braces 22 by brackets 62 and screws 63, as FIGS. 5, 6, 7 and 8 show. To increase the working life of bed 20 and to facilitate movement of the flites 34 and feed along the upper bed surface, the upper bed surfaces may be treated with an anti-friction coating, preferably in the form of a plastic coating, which is painted thereon and allowed to dry during manufacture of the bed. It should be noted that the chain is disposed along the tapered edge of the bed 20A (and above and below both beds 20A and 20B) and that the straight edge of each bed abuts the inside surface of the associated channel member 50 so that feed is unable to fall from the straight edge.

It will be apparent to those skilled in the art that, although a triangularly shaped tapered bed 20A is disclosed and described in detail throughout the specification in connection with the preferred embodiment, bed sections of a shape other than triangular are encompassed by the term "tapered." For example, any bed section having an operative width or widths of generally decreasing dimension in the direction in which the cooperating flites move, and defining an edge or edges from which material may fall, such as a step-shaped bed section, a slotted bed section and a curve-edged bed section are each to be considered a tapered bed section for purposes of this specification. Similarly, a perforated bed section is to be considered as within the scope of the present invention.

Sprocket Assembly

As FIGS. 3 and 4 show, the idler sprocket assembly 40 located at one end of conveyor 14 comprises idler sprocket 44 about which chain 33 is reeved. Idler sprocket 44 is rotatably mounted on and near one end of an idler sprocket shaft 70 which has its ends supported on support blades 71 which are rigidly attached to the coupling members 52 at the end of conveyor 14. A collar 72 having a set screw maintains sprocket 44 in proper position on shaft 70 and spacer washers 75 are disposed between the sprocket and a support bracket 71. Shaft 70 is secured in place by a pin 69 which extends through the shaft and a collar 68 on the shaft. A cover 73 is provided for sprocket assembly 40 and is

detachably secured to the end of conveyor 14 by bolts 74.

As FIGS. 4 through 8 show, the drive sprocket assembly 42 located at the other end of conveyor 14 comprises a chain drive sprocket 46 which is rigidly secured, as by a set screw 80, near one end of and is rotatable with a drive shaft 81 which has its ends journaled for rotation in anti-friction bearings 82 which are mounted in pillow blocks 83. Each pillow block 83 is rigidly secured to one end of a channel-shaped adjustable support member 85 which is provided with slots 86 for receiving bolts 87 to secure member 85 to the outside of the channel member 50. Loosening of the bolts 87 permits both members 85 to be slidably moved forward or rearward to maintain the proper amount of slack in chain 33. The construction and arrangement of the members 85 also facilitates attachment or detachment of chain 33 during assembly or disassembly of conveyor 14. A set screw 89 for locating and holding member 85 in a precise location bears against the rear end of member 85 and is in threaded engagement with and extends through a threaded hole in the forwardly facing flange of a member 90 which is welded to the outside of channel member 50. An adjusting nut 91 is provided on the set screw.

Each member 85 has an upwardly extending motor support plate 93 rigidly secured thereto as by welding and motor mount bars 94 are rigidly connected between the plates as by bolts 95. Motor 45 is adjustably secured to the bars 94 by bolts 96.

A cover 98 is provided for sprocket assembly 42 and is detachably secured to the end of the feeder conveyor by bolts 99. One end of drive shaft 81 extends through its bearing 82 to a point outwardly of a side of conveyor 14 and a relatively large driven roller chain sprocket 100 is rigidly secured to the shaft.

The Chain-Flite Assembly

As FIGS. 5, 6 and 7 show, the chain-flite assembly 32 comprises a single endless link type chain 33 which extends substantially along the entire length of conveyor 14 alongside one edge of bed 20. The chain 33 comprises individual generally U-shaped links 102 and adjacent links are flexibly interconnected. Chain 33 is provided with the flites 34 which are rigidly attached to the chain at spaced apart intervals therealong and extend transversely of bed 20. Each flite 34 takes the form of a flat rectangular piece of metal which has one end welded to an associated link 102 and a generally triangularly shaped gusset 103 is welded between each flite and its associated link to strengthen the connection. Chain 33 is reeved around the sprockets 44 and 46 and the upper side of the chain slides along chain support member 56. Those flites 34 on the upper side of the chain slide along the upper surface of bed 20 and those flites on the lower side of the chain travel beneath the bed as the chain is moved.

The Adjustable Elbow

As FIGS. 1, 2, 9, 10, 11, 12, 13 and 14 show, there is provided an adjustable elbow 200 in accordance with the present invention for connecting the juxtaposed ends of the two adjacent conveyor sections 14A and 14B to permit those sections to be adjustably positioned in a desired angular relationship vertically with respect to each other and about a horizontal axis.

The adjustable elbow 200 comprises two pivotally interconnected elbow sections 201 and 202 each of which is rigidly connected to the inner end of one conveyor section 14B and 14A, respectively, or by bolts 103. Elbow section 201 (connected to section 14B) comprises a pair of laterally spaced apart side plates 205, fabricated from sheet metal, which are rigidly interconnected by a cross brace 206, in the form of an angle iron welded therebetween. Brace 206 is provided with a smaller angle iron 204 which is welded thereto and affords support for an end of the bed 20B of the associated conveyor section 14B which rests thereon and is secured thereto by bolts 63. Elbow section 202 (connected to section 14A) comprises a pair of laterally spaced apart sheet metal side plates 207 which overlap the plates 205 and which are rigidly interconnected in the form of an angle iron welded therebetween. Brace 208 is provided with a smaller angle iron 209 which is welded thereto and affords support for an end of the bed 20A of the associated conveyor section 14A which rests thereon and is secured thereto by bolts 63.

A horizontal upper shaft 211 extends through holes 215 in the side plates of the two elbow sections 201 and 202 and serves as a pivot shaft about which the two elbow sections (and attached conveyor sections) are adjustably pivotable. As FIG. 14 best shows, shaft 211 is secured against axial and rotational movement at one end by a collar 230 which is welded to the outer surface of one side plate 207 and has set screws 231 and 232 which tighten against shaft 211. Upper chain guide roller 216 is rotatably mounted on shaft 211 and is secured against axial movement thereon by a collar 240, having a set screw 241, which is secured on shaft 211. Collar 240 bears against the inner side of the hub of roller 216 and spacer or shim washers 243 and a bushing 233 are mounted on shaft 211 between the outer side of the hub of roller 216 and the inner surface of wall 205. The elbow sections 210 and 202 are pivotably movable with respect to each other about shaft 211 and the roller 216 is rotatable on shaft 211.

A horizontal lower shaft 214 extends through holes 250 in the side plates 205 of elbow section 201 and is connected therebetween below the upper shaft 211. As FIG. 14 best shows, shaft 214 is secured against axial and rotational movement at one end by a collar 251 which is welded to tighten the outer surface of one side plate 205 and has set screws 252 and 253 which tighten against shaft 214. Lower chain guide roller 220 is rotatably mounted on shaft 241 and is secured against axial movement thereon by a collar 260, having a set screw 261, which is secured on shaft 214. Collar 260 bears against the inner side of the hub of roller 220 and spacer or shim washers 263 and a bushing 255 are mounted on shaft 214 between the outer side of the hub of roller 220 and the inner surface of wall 205. Roller 220 is rotatable on shaft 214. The upper and lower sides of the chain 33 ride on the upper sides of the upper and lower chain guide rollers 216 and 220, respectively. The links 102 of chain 33 are constructed so as to enable a portion of the rollers 216 and 220 to extend between the spaced apart sides of the links. A curved flite guide shield 222 is located on the side plate 205, which plate supports the lower shaft 214. The shield is disposed above the latter shaft to prevent interference with the flites 34 being moved by the chain 33 below bed 20. Overlapping tilt shields 226 and 228 are connected to the cross braces 206 and 208, respec-

tively, on the two elbow sections to bridge the gap between the ends of the bottom beds on the juxtaposed conveyor sections. Shield 226 in the embodiment shown takes the form of the integrally formed projecting side of an angle iron member 206. Shield 228 takes the form of a curved member secured as by welding to the upper and lower projecting edges of angle iron member 208. Shield 228 is of sufficient length so as to extend beneath shield 226 in all operative positions of elbow 200. The shields 226 and 228 are slotted as at 270 to accommodate the upper side of chain guide roller 216.

It should be noted that the upper shaft 211 and the lower shaft 214 are both affixed to elbow section 201 and, as a consequence, never change their relative distance or position with respect to each other. The same holds true for the chain guide rollers 216 and 220 mounted for rotation on the shafts 211 and 214, respectively. Thus, as the conveyor sections 14A and 14B are pivotably moved with respect to each other about the axis of upper shaft 211, the chain 33 still maintains a constant or fixed distance between its upper and lower sides. As a result, there is no substantial change in the distance between upper shaft 211 and either idler shaft 70 at one end of conveyor 14 or driven shaft 81 at the other end of the conveyor. Therefore, there is no binding of chain 33 as the conveyor sections are movably adjusted. Since chain 33 is made up of links which are relatively movable or adjustable with respect to each other, relative movement of the conveyor sections about the axis of shaft 211 results in the links on one side of the chain sliding together and in effect shortens that side of the chain, whereas the links on the other side of the chain tend to pull apart to the fullest extent possible. However, this condition is only observable when the chain is stationary. During movement of the chain when the conveyor is operating, certain links in the chain are always under tension because of the action of the sprockets.

The Drive Assembly

As FIGS. 4 through 8 show, electric motor 45, which, for example, is a two horse-power single-phase motor of a conventional type, is rigidly mounted on the motor mount bars 94 above the remote end of section 14A of conveyor 14. The shaft 105 of motor 45 is provided with a relatively small pulley 106 which is secured thereto by a set screw 107. A V-belt 108 is reeved around pulley 106 and also around a relatively larger pulley or sheave 110 which is rigidly connected as by welding to a relatively small sprocket 115 and both are rotatable on bushings 116 on an intermediate stub shaft 112 which is stationarily mounted on a support 113 on the side 30 of feeder conveyor 14. A collar 109 having a set screw 111 is disposed on the end of shaft 112 to maintain the sheave 110 on the shaft. A roller chain 120 is reeved around sprocket 115 and around the larger sprocket 100. An adjustably movable idler sprocket 124 is rotatably mounted on a bracket 121 provided on member 85 on supporting framework 18 and engages the upper side of roller chain 120. Idler sprocket 124 is adjustably movable, as by loosening bolt 123, to adjust the tension of roller chain 120.

Motor 45 is supplied with electrical power from a suitable source through an electrical cable 130 and is controlled for operation in one direction by control means, including a conventional on-off push-button

switch 48. Switch 48 is mounted on the motor 45, as shown, so as to be readily accessible to the person operating the conveyor 14, but could be located in some other convenient or desirable location. The V-belt 108 and roller chain 120 of drive assembly 23 and the associated pulleys and sprockets are provided with a protective cover 132, as shown in FIG. 1.

The Adjustable Hopper-Leveler Assembly

The drivable chain-flite assembly 22 of conveyor 14 is capable of conveying and distributing feed from either or both adjustable hopper-levelers 16. Each hopper-leveler 16 receives feed from its associated silo S1 and S2, deposits it on bed 20B of section 14B, and levels the feed as it is moved or transported from beneath the hopper toward conveyor section 14A by the flites 34. Each hopper-leveler 16 is mounted on top of supporting framework 18 of section 14B and cover 24 is omitted in these regions.

As FIGS. 15 through 19 show, each adjustable hopper-leveler 16 comprises a pair of spaced apart stationary upright end walls 150 to which generally L-shaped mounting brackets 152 are secured by bolts 154. The brackets 152 are attached to conveyor section 14B by bolts 155. The end walls 150 may be rigidified by two rigid bars 169 which extend therebetween and are secured thereto by bolts 185. A pair of spaced apart generally upright, but inwardly and outwardly pivotably movable side walls 157 are mounted between the pair of end walls 150, as by bolts 159 which extend through holes in the end wall and through holes in inwardly turned side flanges 160 along the side edges of the side walls. Each side wall 157 is independently positionable with respect to the other so as to adjust the bottom spacing therebetween and, thereby, the direction of feed being deposited from hopper-leveler 16 onto bed 20B. More specifically, adjustably swinging and locating both movable side walls 157 in the same direction to a desired position has the effect of directing the feed flow laterally on the conveyor to a desired part of bed 20B. Each movable side wall 157 is provided on its outside surface (and near its end edges) with a pair of L-shaped brackets 164 which are welded thereto. A flat positioner bar 163 is pivotally connected at its inner end by means of a bolt 165 to a bracket 164. Each positioner bar 163 is provided with a series of spaced apart holes 168 therethrough. Each hole 168 in a positioner bar 163 is engageable by a bolt 168a which extends through holes in an end wall 150 and in an associated bracket 152. Thus, with the bolts 168a removed, each side wall 157 can be moved to an appropriate position and then rigidly secured in place therein by insertion of the associated bolts 168a through the appropriate holes 168 in the positioner bars 163 for that side wall.

If preferred, each positioner bar 163 can take the form of an L-shaped member having an elongated hole or slot instead of a series of spaced apart holes 168 for engagement by bolt 168. In such case, the positioner bar need not be pivotally connected, as by brackets 164, to a side wall 157 but need only bear thereagainst to maintain the side wall in adjusted position i.e., to prevent the wall from swinging outwardly.

A feed leveler 180 is provided at one end of each hopper-leveler 16 and is pivotably connected thereto. Each leveler 180 comprises a leveler member 181 in the form of a piece of rigid sheet metal having a generally flat upper portion 181A, a downwardly depending

intermediate portion 181B, and an upwardly extending end portion 181C. Portions 181B and 181C cooperate to define a leveling edge 181D along the underside of the leveler 180. Upper portion 181A is provided at the edge thereof closest to the associated hopper end wall 150 with a pivot shaft or bar 183 which is welded thereto and has its ends journaled in hinges 184 which are rigidly secured by bolts 185 to the bracket 152 at the associated end wall 150. Each leveler member 181 has a support bar 190 which is rigidly secured as by welding to the undersurface of intermediate portion 181B and which extends sufficiently far beyond each side thereof so as to be able to rest on the top edges of the sides 30 and 31 of conveyor section 14B. When a leveler 180 is in working position, leveling edge 181D is positioned a very small distance above the flites passing therebeneath, as FIG. 11 shows. Thus, if a mound of feed is being moved along by a flite 34 beneath the edge 181D, the top of the mound is scraped back into the space ahead of the next oncoming flite 34. This spreads the feed across the width of the bed to assure the even distribution of feed along the length of the bunk. Each leveler 180 is movable between its operating position wherein it is supported just above the flites 34 and a raised position, as shown in FIG. 10, whereby limited access to the interior of conveyor section 14B is afforded to the operator. The levelers 180 also serve as a protective cover for that portion of bed 20B which is not provided with a conventional cover 24.

Operation

Assume initially that conveyor 14 is not in operation and that no feed is being supplied to either hopper-leveler 16 from the silos S1 or S2. Further assume that the movable side walls 157 of each hopper-leveler 16 have been adjusted or placed in a desired position by the operator and that the levelers 180 are down and in operating position. The operator then actuates switch 48 to cause motor 45 to rotate and move the chain-flite assembly 22 in the desired direction. After this, the operator actuates or opens the chute on either or both silos S1 and S2 to continuously supply feed to either or both hopper-levelers 16. Feed is deposited from hopper-leveler 16 onto bed 20B of conveyor section 14B and is moved by the flites 34 on the upper side of chain 33 from beneath the hopper-leveler 16 toward the end of the conveyor section 14A along bed 20B of section 14B. As feed is moved by the flites 34 beneath edge 181D of the operative leveler 180, leveling of the feed occurs as hereinbefore described. As the flites 34 continue to move feed onto and along tapered bed section 20A of section 14A, feed spills off the tapered edge of bed 20A and into bunk 10 and is evenly distributed along the bunk. When a sufficient amount of feed has been evenly distributed in bunk 10, the operator closes the silo chutes so that feed is no longer supplied to the hopper-levelers 16, and when all feed deposited on conveyor 14 has been distributed to the bunk 10 the operator turns off motor 45 of conveyor 14 by means of switch 48. The aforescribed cycle of operation may be repeated as often as necessary to fill bunk 10.

I claim:

1. In a conveyor: a pair of conveyor sections disposed in end-to-end relationship and each comprising a bed section which is of general U-shape in cross section and having a bed, each bed section having a chain sprocket

rotatably mounted adjacent its end remote from the other bed section, a movable endless flexible chain reeved around said sprockets and movable lengthwise in said bed sections; a plurality of flites attached at spaced apart intervals along said chain and extending transversely to said bed sections, the flites on the upper side of said chain being above said beds and the flites on the lower side of said chain being below said beds; and an adjustable elbow connected between the juxtaposed ends of said conveyor sections to enable relative pivotal movement between said conveyor sections, said elbow comprising; a pair of elbow sections, each elbow section being connected to an end of a conveyor section; pivot shaft means for pivotally connecting said pair of elbow sections; a rotatable upper chain guide roller mounted on said pivot shaft means and having an upper side extending above said bed and on which roller the upper side of said chain rides; a rotatable lower chain guide roller mounted on one of said elbow sections below said upper chain guide roller and having an upper side on which the lower side of said chain rides; and tilt shield means on said elbow located above said pivot shaft and below the upper side of said chain and extending between the juxtaposed ends of said bed sections to bridge the gap therebetween.

2. A conveyor according to claim 1 wherein each elbow section comprises a pair of laterally spaced apart side walls and wherein said pivot shaft means comprises a single pivot shaft which is connected between said side walls.

3. A conveyor according to claim 2 including a second shaft connected between the side walls of one of said elbow sections and wherein said lower chain guide roller is mounted on said second shaft.

4. A conveyor according to claim 3 wherein said tilt shield means comprises a pair of overlapping members, each member being connected to one elbow section.

5. A conveyor according to claim 4 wherein each member of said tilt shield means extends between the spaced side walls of its associated elbow section, and wherein each said member is provided with a slot accommodating the upper side of said upper chain guide roller.

6. A conveyor according to claim 4 including flite guide means connected to one elbow section above a portion of said second shaft and below the path of movement of the flites on the lower side of said chain.

7. A conveyor according to claim 3 including a bracing member extending between the side walls of each elbow section, said bracing member serving as a support for the end of the bed section in its associated conveyor section.

8. In a conveyor: a pair of conveyor sections disposed in end-to-end relationship and each comprising a supporting framework including spaced apart side walls, a bed section disposed between said side walls and a chain sprocket mounted on said framework; said bed sections being of generally U-shaped in cross section and having a bottom bed, a movable endless flexible chain reeved around said sprockets and extending lengthwise of said conveyor along one lateral side of said bed sections; a plurality of flites attached at spaced apart intervals along said chain and extending transversely to said bed sections, the flites on the upper side of said chain being above said bottom beds; and an adjustable elbow connected between the juxtaposed ends

of said conveyor sections to enable relative pivotal movement between said conveyor sections, said elbow comprising: a pair of elbow sections, each elbow section comprising a pair of laterally spaced apart side walls; each elbow section being connected to an end of a conveyor section; a pivot shaft for pivotally connecting the side walls of said pair of elbow sections; a rotatable upper chain guide roller mounted on said pivot shaft and having an upper side extending above said bottom beds and on which roller the upper side of said chain rides; a second shaft connected between the side walls of one of said elbow sections below said upper chain guide roller; a rotatable lower chain guide roller mounted on said second shaft and having an upper side on which the lower side of said chain rides; and tilt shield means comprising a pair of overlapping members, each member being connected to one elbow section above said pivot shaft and below the upper side of said chain and extending between the spaced side walls of its associated elbow section, each said member being provided with a slot for accommodating the upper side of said upper chain guide roller, said tilt shield means extending between the juxtaposed ends of said bed sections of said conveyor sections bridge the gap therebetween.

9. A conveyor according to claim 8 including a bracing member extending between the side walls of each elbow section, said bracing member serving as a support for the end of the bed section in its associated conveyor section.

10. A conveyor according to claim 9 wherein one of said bed sections extends between and abuts the side walls of the supporting framework of its associated con-

veyor section, and wherein the other of said bed sections is tapered and has one edge abutting one side wall of the supporting framework of its associated conveyor section.

5 11. An adjustable elbow for a conveyor comprising: a pair of elbow sections; a pivot shaft for pivotally connecting said pair of elbow sections; an upper chain guide roller mounted on said pivot shaft; a lower chain guide roller mounted on one of said elbow sections below said upper chain guide roller; tilt shield means mounted on at least one elbow section and extending above said pivot shaft, said upper roller extending above said shield means.

10 12. An adjustable elbow according to claim 11 wherein each elbow section comprises: a pair of laterally spaced apart side walls between which said pivot shaft extends, and a second shaft extending between the side walls of one of said elbow sections and upon which said lower chain guide roller is mounted.

15 13. An adjustable elbow according to claim 12 wherein said tilt shield means comprises a pair of overlapping members, each member being connected to one elbow section.

20 14. An adjustable elbow according to claim 13 wherein each elbow section comprises a bracing member extending between the side walls thereof, and wherein each overlapping member of said tilt shield means is connected to its associated bracing member.

25 30 15. An adjustable elbow member according to claim 13 wherein said overlapping members define cut-out portions to accommodate said upper chain guide roller.
